UNITED STATES PATENT OFFICE

2,439,057

DOOR OR DRAWER LATCH

Fred J. Russell, Beverly Hills, Calif., assignor to
 Weiser Company, South Gate, Calif., a corporation of California

Application January 21, 1947, Serial No. 723,314

10 Claims. (Cl. 292—75)

1

This invention relates to latch or catch devices for latching doors and is adapted for all types of doors, such as house doors, panel doors, cabinet doors, windows, transoms and the like, either of hinged or sliding hand type, and is also applicable to drawers for desks, dressers and the like.

An object of the invention is to provide a simple, practical and efficient latching device for doors, drawers, windows, and other hinged or sliding structural elements.

Another object of the invention is to provide an improved and simplified latching device adapted to so function as to prevent rattling of the door or other structure on which it is mounted.

A further object of the invention is to provide in a latching device novel structural features incorporating spring seated latch elements whereby the latch may be retained in engagement with the recess or aperture of the striker plate.

A further object of the invention is to provide a latch assembly for doors, windows and the like which includes a ball or roller element spring-seated in a plunger, which plunger is separately spring-seated in the assembly.

Another object of the invention is to provide a door latch device as in the previous objects wherein there is a differential spring mounting of the ball or roller element and the plunger having significant advantages over previously known structures.

Another object of the invention is to provide an improved latch device wherein the structure will have a long life and in which there are no parts which will get out of adjustment or out of order.

Another object of the invention is to provide improved and novel features in a mounting plate and retaining shell or a latch device which results in a reduced cost thereof and assembly of the parts is expedited.

An additional object is to provide a latch device which can be mounted either in a door structure or in a jamb of the door frame and the striker plate can be mounted on the opposite member.

An important object of the invention is the provision of self adjusting features in a latch of the general character disclosed, wherein a factory pre-set tension of the spring elements is adequate for correct functioning of the latch under varying conditions of installation, without the necessity of adjustment, the self adjusting features comprising a plunger, a spring between the plunger and the ball or other latch contact

2

ing element, and a second spring on the opposite side of the plunger, whereby initial external pressure on the ball is absorbed by the first spring to the limit of travel represented by the normal spacing between ball and plunger, and continued pressural shifting of the ball is transmitted by the plunger against and yieldably resisted by the second spring.

Other objects and advantages will appear and be brought out more fully in the following specification considered with reference to the accompanying drawings throughout which like parts are designated by like numerals.

In the drawings:

15 Figure 1 is a vertical section view taken through a door and jamb showing the invention.

Figure 2 is a plan section taken along the line 2—2 of Figure 1.

Figure 3 is a view similar to Figure 2 showing the latch mechanism in fully extended position.

Figure 4 is an end view as seen and indicated by the arrow and numeral 4 of Figure 3.

Figure 5 is a similar view as seen from the arrow 5 of Figure 3.

25 Figure 6 is an enlarged sectional view taken along the line 6—6 of Figure 3.

Figure 7 is a perspective view showing a mounting plate and tubular member of the latch device of Figures 1 to 6.

30 Figure 8 is a view similar to Figure 7 showing a modified form of mounting plate and retaining shell.

Figure 9 is a perspective view, partly broken away, showing further modified forms of mounting plate, shell and retaining member.

Figure 10 is a perspective view showing a modified form of striker plate.

Figure 11 is a fragmentary view illustrating the contact element and retaining member in several 40 positions during movement in engagement with the striker plate.

Figure 12 is a side view, partly in section, showing a modified form of retaining member.

Figure 13 is a side view, partly in section, showing another modified form of retaining member.

Figure 14 is a perspective view showing a modified form of my invention incorporating a roller contact element.

50 Figure 15 is a sectional view taken along the line 15—15 of Figure 14.

Figure 16 is a view similar to Figure 12 showing a further modified form of contact element.

Figure 17 is a view similar to Figure 2 showing 55 a further modified form of my invention having

gravity actuated contact and retaining member elements.

Referring more particularly to the drawing I show a mounting plate 10 adapted to be secured as by screws 11 to the edge of a door or jamb and having a central opening 12. Plate 10 is formed with a pair of arcuately shaped cutouts 13 disposed on opposite sides of opening 12. A retaining shell which may comprise a tubular housing 14 is formed with a pair of arcuately formed end portions 15 which extend through cutouts 13, plate 10 having a pair of arcuate abutment portions 16 for the end portions 15a between portions 15. The two pairs of end portions 15 and 15a form firm securing means for housing 14 on plate 10 in alignment with aperture 12, portions 15 being pressed outwardly after positioning through cutouts 13.

Housing 14 has a plurality of inwardly turned end flange portions 17 which form a seat for a coil compression spring 18. A tubular plunger 20 is slidably disposed in housing 14 and seats against spring 18 and has an end extension 21 which extends partially into the reduced end portion of the coils of spring 18. Plunger 20 has an end portion 22 of a diameter to permit movement through opening 12 of plate 10, the plunger being shaped with an annular abutment 23 engageable with portions 16 of plate 10 to limit the outward movement of the plunger, the plunger having a rim portion 24 which is coined inwardly to provide a seat stop for a ball member 25 which is movable within the bore of the plunger. A coiled spring 26 is disposed within the bore of plunger 20 and is of a reduced spiral formation, the reduced end bearing against ball 25 to urge the ball in extended position in engagement with rim 24, as shown in Figure 3. Plunger 20 is provided with a stop abutment 27 against which ball 25 may seat, upon retracted movement during operation, such that upon further retractive movement of the ball member 25, plunger 20 will be moved inwardly within housing 14 against the action of spring 18, as shown in Figures 1 and 2.

Figures 1 and 2 show a striker plate 30 mounted as by screws 31 to the face of the complementary door or jamb member, the striker plate having a recess 32 into which ball member 25 may seat to provide the restraining or latching features of the device, plate 30 also being formed with an angularly disposed guide or cam portion 33 which, when the door is moved to closed position, engages ball 25 and effects the retractive movement of the ball and plunger members.

The formation and association of the striker plate, ball contact element and plunger or retaining member are such that, during this movement, the striker plate is engaged solely by the contact member and is free from engagement with the retaining member. The retaining member is retracted against the action of spring 18 when the contact element 25 seats against abutment 27.

In Figure 8 I show a modified form of mounting plate and retaining shell. In this figure I show a mounting plate 35 having a substantially circular opening 36 but having a pair of abutment portions 37 of somewhat less spacing than the diameter of opening 36. The retaining shell 38 has end portions 39 which, in the assembly, extend through opening 36 and end portions 40 which, in the assembly, abut and engage abutment portions 37 of the striker plate, end portions 39 being pressed outwardly in engagement with the outer face of plate 36 and provide a secure mounting for the retaining shell 38 in a man-

ner which is effectively similar to the structure of Figures 1 to 7.

In Figure 9 I show another modified form of retaining shell and mounting plate. In this figure the mounting plate 41 is formed with a circular opening 42, a tubular member or retaining shell 43 being formed with alternate pairs of end portions 44 and 45, portions 45 being bent outwardly to form abutting flanges at the rear side of plate 10 41, end portions 44 being extended through aperture 42 in assembly and bent or pressed outwardly against the outer face of plate 41, forming holding flanges. The tubular retaining shell 43 is thus securely held to the mounting plate 41 by the pairs of flanged end portions.

Figure 9 shows a modified form of plunger assembly wherein a plunger member 46, which retains a ball element 47, is formed with a longitudinal groove or slot 48 in which engages a tab 49 pressed inwardly from a portion of the wall of tubular member 43. The end portions of groove or slot 48 provide abutments which limit the reciprocatory movement of plunger 46 both inwardly and outwardly. Tab 49 may assume other forms than a pressed or bent portion, an equivalent feature being a set screw or other equivalent device providing an abutment for the end portions of groove or slot 48.

Figure 10 shows a modified form of striker plate. The striker plate of Figures 1 and 2 is shown as having a recess or cup, the recess being of such shape and depth as to be engaged by the ball element 25 but not engaged by the plunger 20, the engagement being such that the curve 35 of the recess in the cross-section shown in Figure 2 is substantially the curve of a ball, which engagement prevents rattling of the latch structure when the door or window is in normally closed position. Opening 52 is shown as being elongated vertically, however, the transverse or horizontal dimension thereof is such as to provide engagement with the ball element substantially as shown in connection with recess 32, as shown in Figures 1 and 2.

Figure 11 illustrates somewhat graphically the relative association of the striker plate, contact element and retaining member as the latch is moved into holding position as it functions in a swinging door. As the latch is moved to retaining position ball member 25 engages and moves along cam surface 33 of striker plate 30 and compresses spring 26 and seats against stop abutment 27 of retaining member 20. The dotted line indicates the movement and spacing of the contact element with respect to the surface of the striker plate, the ball contact element 25 moving first inwardly with respect to the retaining member until it engages abutment 27 and thence the retaining member is retracted or moved inwardly and then slightly outwardly as the ball element enters recess 32.

The various features of my invention are subject to variation as to form and relationship and several such variations are illustrated in Figures 12 to 17. Figure 12 shows a modified form of retaining member, the member being indicated as 55 and having a tubular opening or cavity 56 in which a ball contact element 57 is spring-seated and retained by a swaged rim portion 58. This form of the retaining member would be used in connection with the tubular housings 14 or 38 together with mounting plates 10 or 35 having abutments such as 16 or 37 to limit the outward movement of the retaining member.

In Figure 13 I show a further modified form

of retaining member which is substantially similar to that of Figure 12, the retaining member being designated 60 and having a tubular cavity for receiving a ball contact element 61 which is retained by a plurality of resilient fingers or prongs 62 which are bent inwardly and having an effective diametrical opening less than the diameter of ball 61.

In Figures 14 and 15 I show another modified form of latch. In these figures a rectangularly shaped housing 65 is secured to a mounting plate 66 having a rectangular opening 67 through which extend flanged end portions 68 of opposite side walls 69 of the housing 65. A retaining member 70 is spring-seated by a spring 71 in housing 65 and is of rectangular shape and is formed with one or more slots 72 which engage tabs 73 pressed inwardly from sides 69 of the housing 65. A contact element 74 in the form of a roller is provided with a pair of pivot pins 75 which extend into elongated slots 76 formed in the side walls of retaining member 70. A pair of springs 77 suitably secured within retaining member 70 normally urge the roller 74 in extended position. Upon inward movement or retraction by pressure applied against the roller element 74, the roller is first retracted against the pressure of springs 77 and upon reaching the limit of the retracted movement, as determined by the pivot pins 75 in slots 76, the retaining member 70 is retracted inwardly against spring 71 in a manner substantially similar to that of Figures 1 to 11.

In Figure 16 I show another modified form of retaining member. In this figure the retaining member is indicated as 80 and is substantially similar to retaining member 70, however, it is formed to include abutment stop 83 and to include opposite edge portions 81 swaged inwardly to retain a roller element 82, by which construction the pivot pin 75 of roller 74 may be eliminated.

In Figure 17 I show a further modified form of the invention. In this figure I show a tubular housing 85 mounted vertically in a door or jamb 86 and having a mounting plate 87 suitably secured to a lower portion of the door or jamb. A retaining member 88 is formed with a tubular opening 89 in which a ball element 90 is held as by retaining rim portion 91. The retaining member 88 may be provided with a suitable abutment formation 92 to serve as a stop to limit the outward or downward movement of the retaining member 88, which member performs its latching function by gravity which may be increased by additional weight. The complementary jamb or door member 93 may be provided with a striker plate 94 having a retaining aperture 95 or equivalent recess for engagement with contact element 90.

For the purpose of disclosing and explaining what may be a desirable commercial embodiment or embodiments of my invention, it is entirely feasible to fabricate the device in other ways than those shown and described. Thus, the first plate and shell may be formed as one shape, as, for example, in die casting. Another example might be to eliminate the first plate altogether and, while appearance might be thus sacrificed, the shell itself could be formed to function sufficiently as a general retaining member. It is even possible that the shell itself could be eliminated and the latch mechanism consisting of the ball or other contact element and its immediately related functional parts be installed in a hole drilled in a door, door jamb or other structural element.

The essential features or essence of my invention resides in the latch mechanism comprising the four primary parts; namely, the plunger embodying means or retaining the contact element, the contact element itself, and the two springs, one spring having a tension or strength greater than the other which results in a two-stage depression or longitudinal movement of the latch element when external pressure is applied thereto as, for example, when closing a door, the first stage of the movement occurring by the yielding of the spring of weaker tension and the second stage of the movement occurring by the yielding of the spring of the greater tension. In the case of gravitational action, either or both springs may be eliminated in favor of gravitational force.

Preferably, although not necessarily, the relation of the primary parts is such that initial pressure on the ball or contact element results in depression of the weaker spring, the inward motion of the contact element being resisted by said spring. Further pressural movement of the contact element results in a force being transmitted from the ball to the plunger, whereupon the plunger begins to depress the second or stronger spring, the inward motion of the plunger being resisted by the second spring.

Although I have herein shown and described my invention in what I have conceived to be the most practical and preferred embodiment, it is recognized that departures may be made therefrom within the scope of my invention, which is not to be limited to the details disclosed herein but is to be accorded the full scope of the claims so as to embrace any and all equivalent devices and systems.

The term "striker plate" as used in the claims comprehends a striker plate of the general character illustrated and described, or any other suitable type of plate, or a mere structural surface positioned to function in a manner similar to that of a striker plate.

The term "housing" as used in the claims comprehends a housing of the general character illustrated and described, or any other equivalent form, including but not limited to, a socket of suitable size and form provided in the material of the structural body itself in which the remaining specified elements of the latch are located.

Having thus described my invention, what I claim and desire to secure by Letters Patent is:

1. A latch comprising a projectable retaining member adapted when installed in a structural body to advance beyond the surface thereof, said retaining member being formed with a shouldered portion, a floating contact element within said retaining member, said retaining member embodying a stop to limit the inward travel of said floating contact element within said retaining member and embodying an opening through which the contact element may project and embodying limit means to fix the maximum projection of said contact element, and a housing for said retaining member embodying means to limit the advance of the retaining member, said last means including a plate portion of said housing having an opening for the retaining member and having an abutment portion extending into said opening engageable with the shouldered portion of the retaining member.

2. A latch comprising a projectable retaining member adapted when installed in a structural body to advance beyond the surface thereof, a floating contact element within said retaining member, said retaining member embodying a

stop to limit the inward travel of said floating contact element within said retaining member and embodying an opening through which the contact element may project and embodying limit means to fix the maximum projection of said contact element and a housing for said retaining member embodying means to limit the advance of the retaining member, said contact element being spring-loaded.

3. A latch comprising a projectable retaining member adapted when installed in a structural body to advance beyond the surface thereof, a floating contact element within said retaining member, said retaining member embodying a stop to limit the inward travel of said floating contact element within said retaining member and embodying an opening through which the contact element may project and embodying limit means to fix the maximum projection of said contact element and a housing for said retaining member embodying means to limit the advance of the retaining member, said retaining member and contact element each being spring-loaded.

4. A latch comprising a projectable retaining member adapted when installed in a structural body to advance beyond the surface thereof, a floating contact element within said retaining member, said retaining member embodying a stop to limit the inward travel of said floating contact element within said retaining member and embodying an opening through which the contact element may project and embodying limit means to fix the maximum projection of said contact element and a housing for said retaining member embodying means to limit the advance of the retaining member, said retaining member and contact element each being spring-loaded, one of the loading springs being weaker than the other.

5. A latch adapted to be installed in a structural body for cooperation with a striker plate mounted on an adjacent structural body, said latch comprising a slidable retaining member, a contact element longitudinally shiftably mounted in said retaining member, said retaining member being provided with stop means and limit means oppositely spaced relative to the contact element fixing the opposite extremes of shifting movement of the contact element in the retaining member, said contact element extending beyond the end of said retaining member in all positions of said contact element, housing means slidably confining said retaining member and having an open end through which said retaining member can project, whereby when said latch is mounted in a structural body engagement of the contact element with a striker plate will initially cause the contact element to shift longitudinally in the retaining member, and after the limit of such shifting is reached as fixed by said stop means any further movement resulting from engagement of the contact element with the striker plate will cause the retaining member to slide within the housing without permitting the retaining member to engage the striker plate.

6. A latch adapted to be installed in a structural body for cooperation with a striker plate mounted on an adjacent structural body, said latch comprising a slidable retaining member, a contact element longitudinally shiftably mounted in said retaining member, said retaining member being provided with stop means and limit means oppositely spaced relative to the contact

element fixing the opposite extremes of shifting movement of the contact element in the retaining member, said contact element extending beyond the end of said retaining member in all positions of said contact element, housing means slidably confining said retaining member and having an open end through which said retaining member can project, said contact element being spring loaded, whereby when said latch is mounted in a structural body engagement of the contact element with a striker plate will initially cause the contact element to shift longitudinally in the retaining member, and after the limit of such shifting is reached as fixed by said stop means any further movement resulting from engagement of the contact element with the striker plate.

7. A latch adapted to be installed in a structural body for cooperation with a striker plate mounted on an adjacent structural body, said latch comprising a slidable retaining member, a contact element longitudinally shiftably mounted in said retaining member, said retaining member being provided with stop means and limit means oppositely spaced relative to the contact element fixing the opposite extremes of shifting movement of the contact element in the retaining member, said contact element extending beyond the end of said retaining member in all positions of said contact element, housing means slidably confining said retaining member and having an open end through which said retaining member can project, said retaining member being spring loaded, whereby when said latch is mounted in a structural body engagement of the contact element with a striker plate will initially cause the contact element to shift longitudinally in the retaining member, and after the limit of such shifting is reached as fixed by said stop means any further movement resulting from engagement of the contact element with the striker plate will cause the retaining member to slide within the housing without permitting the retaining member to engage the striker plate.

8. A latch adapted to be installed in a structural body for cooperation with a striker plate mounted on an adjacent structural body, said latch comprising a slidable retaining member, a contact element longitudinally shiftably mounted in said retaining member, said retaining member being provided with stop means and limit means oppositely spaced relative to the contact element fixing the opposite extremes of shifting movement of the contact element in the retaining member, said contact element extending beyond the end of said retaining member in all positions of said contact element, housing means slidably confining said retaining member and having an open end through which said retaining member can project, a spring in said retaining member opposing inward shifting of the contact element, and a spring in said housing means opposing inward sliding movement of the retaining member, whereby when said latch is mounted in a structural body engagement of the contact element with a striker plate will initially cause the contact element to shift longitudinally in the retaining member, and after the limit of such shifting is reached as fixed by said stop means any further movement resulting from engagement of the contact element with the striker plate will cause the retaining member to slide within the housing

without permitting the retaining member to engage the striker plate.

9. A latch comprising a projectable retaining member adapted when installed in a structural body to advance beyond the surface thereof and to be retracted within the surface thereof, said retaining member providing a mounting for a floating contact element and having an open end through which such contact element may project, a floating contact element mounted in said retaining member and projecting through said open end, said retaining member embodying a stop to limit the inward travel of said contact element, and a limit means to fix the maximum projection of said contact element, said stop and said limit means being spaced in relation to the contact element so that substantial movement of the contact element longitudinally of the retaining member is permitted, the stop being positioned in relation to the open end of the retaining member so that at the limit of the inward movement of the contact element relative to the retaining member the contact element still projects beyond the said end of the retaining member and prevents engagement of said end of the retaining member with an external object located outside of the structural body in proximity thereto such as a striker plate, a housing slidably confining said retaining member, and means cooperating between said housing and said retaining member limiting the advance of said retaining member outwardly from said housing.

10. A latch comprising a projectable retaining member adapted when installed in a structural body to advance beyond the surface thereof and to be retracted within the surface thereof, said retaining member providing a mounting for a floating contact element and having an open end through which such contact element may project, a floating contact element mounted in said retaining member and projecting through said open end, said retaining member embodying a stop to limit the inward travel of said contact ele-

ment, and a limit means to fix the maximum projection of said contact element, said stop and said limit means being spaced in relation to the contact element so that substantial movement of the contact element longitudinally of the retaining member is permitted, the stop being positioned in relation to the open end of the retaining member so that at the limit of the inward movement of the contact element relative to the retaining member the contact element still projects beyond the said end of the retaining member and prevents engagement of said end of the retaining member with an external object located outside of the structural body in proximity thereto such as a striker plate, a housing slidably confining said retaining member, and means cooperating between said housing and said retaining member limiting the advance of said retaining member outwardly from said housing, said last named means comprising a flange on said housing and a shoulder on said retaining member.
